UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed May 17, 1930. Serial No. 453,364.

My invention relates to railway traffic controlling apparatus, and particularly to apparatus of the type involving a railway switch and the signal governing traffic over the switch.

More specifically, my invention relates to the approach locking of a switch, and has for an object the provision of novel and improved approach locking means whereby 10 momentary release of the track relay for the section including the switch will not result in false operation of the approach locking apparatus.

I will describe two forms of apparatus 15 embodying my invention, and will then point out the novel features thereof in claims.

In the accompanying drawings, Fig. 1 is 20 a diagrammatic view showing one form of apparatus embodying my invention. Fig. 2 is a diagrammatic view showing a modification of a portion of the apparatus shown in Fig. 1 and also embodying my invention.

Similar reference characters refer to similar parts in each of the views.

Referring first to Fig. 1, the reference characters 1 and 1^a designate the track rails of a stretch of main track A, which rails are divided by insulated joints 2 to form 30 a main section U—V, a first approach section Y—U, and a second approach section W—Y. The main section U—V is provided with a switch B leading into a side track C. Traffic moving toward the right over switch B is governed by two signals S¹ and S², controlled in part by the usual home relays H¹ and H², respectively. The switch B is provided with an operating mechanism D, which is controlled in part by a polarized 35 switch relay M.

Each track section is provided with the usual track circuit, comprising a battery 3 connected across the rails at the right-hand end of the section, and a track relay connected across the rails at the left-hand end of the section and designated by the reference character T with a distinguishing exponent. The first approach section Y—U is provided with an insulated joint 2^a near the right-hand end of the section, and an

auxiliary track relay E is connected with the rail 1^a on opposite sides of this joint. It follows that relay E is energized at all times except when some portion of a train occupies the space between the insulated joint 2^a and the point U.

Relay E controls a slow-releasing relay F, the circuit being from terminal *x* of a suitable source of current, through back contact 4 of relay E, and the winding of relay F to terminal *o* of the same source of current.

The reference character P designates the usual approach locking relay, the circuits and function of which will be explained hereinafter.

Signal S¹ is provided with an operating circuit which includes a front contact 5 of relay H¹, so that this signal can not indicate "proceed" unless the relay is energized. Signal S² is controlled in similar manner by a front contact 6 of relay H². Relays H¹ and H² are controlled in the usual manner from a distant point, such as an interlocking tower or a despatcher's office, and the circuits for these relays include a front contact 16 of track relay T¹, so that both relays will be deenergized when a train occupies the main track section U—V.

The switch operating mechanism D is controlled by the polarized switch relay M in such manner that the switch occupies one position or the other according as relay M is energized in one direction or the other, this control being accomplished by a neutral contact 18 and a polarized contact 17 of relay M. The control of the switch mechanism by relay M forms no part of my present invention. Relay M will usually be controlled from the same remote point as the signal relays H¹ and H², and the circuit for relay M includes a front contact 15 of the approach locking relay P, so that relay M cannot be energized to operate the switch B unless relay P is energized.

Relay P is provided with a main pick-up circuit which passes from terminal *x*, through back contact 7 of relay H¹, back contact 8 of relay H², front contact 9 of track relay T², front contact 10 of track relay T³, and the winding of relay P to

terminal σ . Relay P is provided with an auxiliary pick-up circuit which passes from terminal α , through back contacts 7 and 8 of relays H^1 and H^2 , back contact 11 of track relay T^1 , front contact 12 of auxiliary track relay E, front contact 13 of slow-releasing relay F, and the winding of relay P to terminal σ . Relay P is also provided with a stick circuit which passes from terminal α , through back contacts 7 and 8 of relays H^1 and H^2 , front contact 14 of relay P, and the winding of relay P to terminal σ . An emergency pick-up circuit is provided for relay P, which passes from terminal α , through back contacts 7 and 8 of relays H^1 and H^2 , normally open contact of a manually operable time release device G, and the winding of relay P to terminal σ .

The operation of the apparatus is as follows: Assuming that switch B is in normal position, and that there are no trains on the portion of track shown in the drawing, the operator at the remote point may clear signal S^1 by closing the circuit for relay H^1 . This will open all of the circuits for relay P at back contact 7 of relay H^1 , so that relay M cannot be energized to reverse the switch B. If the operator desires to reverse this switch before a train moving toward the right passes point W, he may do so by first opening the circuit for relay H^1 , thereby restoring signal S^1 to the stop position. If, however, a train has entered section W-Y and is at any point between W and U, the opening of the circuit for relay H^1 will not permit the switch to be reversed, because the main pick-up circuit for relay P will be open at front contact 9 or 10 of track relay T^2 or T^3 .

When the train moving toward the right passes insulated joint 2^a , relay E will become deenergized, and this will result in causing relay F to become energized. When the front end of the train enters section U-V, track relay T^1 will become deenergized, thereby opening the circuit for relay H^1 , so that signal S^1 will move to the stop position. When the rear end of the train passes point U, both relays E and T^2 will become energized, but relay F will remain closed for a short interval of time, due to its slow-releasing characteristic. During this short interval of time the auxiliary pick-up circuit for relay P will be closed through contacts 11, 12 and 13 of relays T^1 , E and F, respectively. As soon as relay P becomes energized due to this pick-up circuit, its stick circuit will become closed. The energization of relay P causes the approach locking for switch relay M to be released.

The purpose of the time release device G is, of course, to permit emergency energization of relay P while a train occupies

either of the approach sections W-Y or Y-U.

Referring now to Fig. 2, the apparatus shown in this view is the same as that shown in Fig. 1, except as to the means for controlling the auxiliary pick-up circuit for relay P. In Fig. 2, track battery 3 for the first approach section Y-U is connected across the rails at the left-hand end of the section, and the track relay T^2 is connected across the rails at the right-hand end of the section. Slow-releasing relay F is controlled by a back contact 4^a of track relay T^2 . The auxiliary pick-up circuit for relay P is from terminal α , through back contacts 7 and 8 of relays H^1 and H^2 , back contact 11 of track relay T^1 , front contact 12 a of track relay T^2 , front contact 13 of relay F, and the winding of relay P to terminal σ .

The operation of the apparatus shown in Fig. 2 is substantially the same as that of the apparatus shown in Fig. 1. That is to say, when the rear end of a train moving toward the right passes point U, track relay T^2 will become energized, but relay F will remain closed for a brief interval of time, and during this interval of time the auxiliary circuit for relay P will be closed.

The apparatus shown in Fig. 1 comprises a stretch of railway track including a switch and an insulated joint, a relay connected across the joint, and means controlled by the relay for controlling the switch. Another system embodying a feature of this general character is disclosed and claimed in a copending application of common ownership, Serial No. 428,347, filed Jan. 25, 1930, by John M. Pelikan, for railway traffic controlling apparatus.

One feature of my invention is that the approach locking for the switch B will not be falsely released in the event of momentary release of the track relay T^1 , or in the event of any other abnormal operation of this relay. This is due to the fact that when a train passes along the stretch of track shown in the drawing, relay P can become energized only during the short interval of time between the instant that the rear end of the train passes point U and the instant that slow-releasing relay F opens.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a main section of railway track containing a switch, a track circuit including a track relay for said section, an approach section provided with an insulated joint in one track rail, a track circuit

- for said approach section including a source of current connected across the rails at the exit end and an auxiliary relay connected around said joint, a slow-releasing relay controlled by a back contact of said auxiliary relay, an approach locking relay, means for preventing operation of said switch unless said approach locking relay is energized, and a pick-up circuit for said approach locking relay including in series a back contact of said main section track relay and a front contact of said auxiliary relay as well as a front contact of said slow-releasing relay.
2. In combination, a main section of railway track containing a switch, a track circuit including a track relay for said section, an approach section, a track circuit for said approach section including a track relay connected across the rails at the exit end, a slow-releasing relay controlled by a back contact of said approach section track relay, an approach locking relay, means for preventing operation of said switch unless said approach locking relay is energized, and a pick-up circuit for said approach locking relay including in series a back contact of said main section track relay and a front contact of said approach section track relay as well as a front contact of said slow-releasing relay.
3. In combination, a main section of railway track containing a switch, a track circuit including a track relay for said section, an approach section, a track circuit including a track relay for said approach section, a slow-releasing relay controlled by a back contact of said approach section relay, an approach locking relay, means for preventing operation of said switch unless said approach locking relay is energized, and a pick-up circuit for said approach locking relay including in series a back contact of said main section track relay and a front contact of said approach section relay as well as a front contact of said slow-releasing relay.

In testimony whereof I affix my signature.

LESTER E. SPRAY.
